Primary Examiner — Robert M Spear*Assistant Examiner* — Darcey E Heflin(74) *Attorney, Agent, or Firm* — Collard & Roe, P.C.(57) **CLAIM**

The ornamental design for an electrostimulation apparatus, as shown and described.

DESCRIPTION

FIG. 1 is a top and left perspective of an electrostimulation apparatus, showing my new design;

FIG. 2 is a top plan view thereof;

FIG. 3 is a left side plan view thereof;

FIG. 4 is a right side plan view thereof;

FIG. 5 is a front plan view thereof;

FIG. 6 is a rear plan view thereof; and,

FIG. 7 is a bottom plan view thereof.

In the drawings, the broken lines depict environmental subject matter and form no part of the claimed design.
